HARMONICA

Walter R. Steele, Lemon Grove, Calif.

Application November 21, 1938, Serial No. 241,499

13 Claims.

(CL. 84—377)

My invention relates to musical instruments of the harmonica type and more particularly to the kind using a key transposing type of mouthpiece.

One of the primary objects of my invention is the combination of a key transposing type of mouthpiece with a reed plate assembly of special construction and tuning in order to provide an instrument upon which the complete harmonica scale or a pre-selected combination of notes as chosen by the manufacturer may be played without moving the mouthpiece, together with means located within the mouthpiece for rapidly changing the pitch as in playing sharps and flats, such mouthpiece being adjustably mounted over the reed plate assembly, whereby a different and complete arrangement of notes may be played at each setting of the mouthpiece.

Another object is to provide in an instrument of this type, a mouthpiece which, as arranged by the manufacturer, affords within a wide range, the selection of particular combinations of notes that may be played at any setting of the mouthpiece, such mouthpiece being capable of maintaining a similar combination of tonal relationship and breathing sequence at any pitch of key to which the mouthpiece may be adjusted over the reed assembly.

Another object is to provide an adjustable mouthpiece of the above type, with a slideable air limiting valve interposed within the base of said mouthpiece and means facilitating the rapid manipulation of said valve as required in playing various musical arrangements, including the most difficult, the said air valve being capable of changing the key to obtain sharps and flats, or of otherwise changing the key, as selected by the manufacturer.

Another object is to provide the above type of mouthpiece with finger grips to facilitate the adjusting of the same in selected positions, a locking device to hold said mouthpiece in position and to remove all looseness between said mouthpiece and the reed assembly, and finger operated means for instantly releasing the said locking device to permit free longitudinal movement of said mouthpiece.

Another object is to provide a harmonica mouthpiece with wind saving valves to permit the human breath to flow in one direction and to prevent it from flowing in the opposite direction.

Another object is to provide a mouthpiece of this type with stops and indicating means to aid the player in finding correct position of mouth-

piece when modulating from one key to another while playing.

Generally speaking these improvements have to do with the obtaining of a more rapid technique by the player in playing sharps while rendering a piece of music, such improvements being facilitated through a simplified and more practical form of mouthpiece. Great advantages are also brought about through variations of arrangement of the reeds or notes. Of especial advantage also is an indicator which enables the player to modulate from one key to another while playing the instrument, an effect which is accomplished with a much greater degree of certainty than heretofore. In my improved construction, I find of considerable utility my arrangement in the stick of the cells and reeds whereby I bring about the staggering of the blow and draw notes. Other objects will appear from the drawing and as hereinafter set forth and claimed.

Attention is hereby directed to the drawings, illustrating a preferred form of my invention, in which similar numerals of designation refer to similar parts throughout the several views, and in which—

Figure 1 is a plan view of one form of my improved harmonica, showing the same partly broken away to disclose the location of the reeds on the top reed plate;

Figure 2 is a front elevation of the same;

Figure 3 is a longitudinal section on line 3—3 of the mouthpiece shown in Figure 2, looking in the direction of the arrows;

Figure 4 is a front elevation of one of the stationary valve plates normally mounted within a recess at the rear of the mouthpiece;

Figure 5 is a front elevation of one of the movable valve plates in slideable contact with the plate shown in Figure 4 and within the same recess;

Figure 6 is a modification of the plate shown in Figure 4;

Figure 7 is a modification of the plate shown in Figure 5;

Figure 8 is a front elevation of a portion of the apertured plate permitting admission of air to the reed section;

Figure 9 is a front elevation of the edge of a portion of the reed section, in front of which the apertured plate shown in Figure 8 is normally mounted;

Figure 10 is a section on line 10—10 of the instrument shown in Figure 2, looking in the direction of the arrows;

Figure 11 is a sectional view of one end of the mouthpiece, showing a modified form of lever for operating one of the movable valve plates;

Figure 12 is an enlarged front view of a portion of the mouthpiece showing two air openings, leading to a special form of air cell herein-after described;

Figure 13 is a view of a special form of one of the adjustable stops employed to locate the mouthpiece in the desired position and to limit its movement within desired bounds; and

Figure 14 is a section on line 14—14 of the portion of the mouthpiece shown in Figure 12, looking in the direction of the arrows.

My improved instrument consists of two principal elements: first, a harmonica reed plate assembly of special construction and tuning; and second, a key-transposing mouthpiece mounted over the front edge of the reed-plate assembly to admit air to the reeds in a pre-selected sequence such that a complete harmonica scale or other selected combination of notes may be played without moving the mouthpiece. The mouthpiece is so mounted that it may be moved longitudinally over the reed plate assembly and may be locked in a plurality of different settings. In each setting the relationship between tones and the breathing sequence will be the same, but the pitch will correspond to the various keys.

Referring to the drawings, the reed plate assembly 15 consists of a notched stick 16 with reed-plates 17 and 18 above and below the stick and notches 19 and 20 therein as shown in Figures 9 and 10. Two rows of spaced notches or grooves 19 and 20 pierce the front edge of stick 16 and open out at the upper and the lower sides respectively of stick to form air cells when enclosed by the said reed plates. A middle tongue or separator 21 divides the air cells into two isolated parallel rows. A reed 22 is mounted in the usual manner over each upper cell 19 and likewise a reed 23 is mounted over each lower cell 20. All of the reeds 22 are attached to the upper side of plate 17 and the whole upper row of reeds are played by drawing the breath. The reeds 23 are on the upper side of plate 18, or within the lower cells 20, and the whole lower row of reeds are played by blowing the breath.

In order that unnecessary breath will not be drawn past the reeds 23 when the player is drawing the breath to actuate the reeds 22, a valve 24, in the form of a narrow leather strip, is mounted on the lower plate 18 below each reed 23. When the human breath is blown to produce sound from the reeds 23, the valve 24 will swing clear to allow the reeds to vibrate but when the breath is drawn to actuate the reeds in upper row, the valve 24 will be closed to prevent escape of breath past reeds 23. The escape of breath past reeds 22 is controlled in the mouthpiece and will be hereinafter particularly described. The front edge of reed plate 17 is turned abruptly upward as shown (see Figure 10) to form a narrow guide rib 79. Similarly, the front edge of lower plate 18 is turned downward to provide another guide rib 81.

A flat apertured metal valve plate 25 is mounted over the front edge of said stick and has apertures 26 in the upper edge thereof to admit air to each of the upper cells 19 and apertures 27 in lower edge to admit air to each of the lower cells 20. The upper and lower edges of this plate 25 are turned backwardly and inwardly as at 28 to form small channels so that when the plate is

in place the guide ribs 79 and 81 will ride in such channels. Thus, the reed plates 17 and 18 will be held rigidly against the walls of the stick 16 and at the same time the plate 25 will also be held firmly affixed to the front edge of such stick. A cover 29 is attached to the upper side of the assembly to enclose and protect the reeds on the upper reed plate 17 and a similar cover is secured to the lower side below the lower reed plate 18, the covers being held in place by screws 30 at each end of the assembly. The rear edges of these covers are perforated as at 31 to allow the issuance of musical sounds.

The above description covers the structure of the reed plate assembly, and the special tuning of the reeds will now be described. All of the reeds on the upper plate 17 are played by drawing the breath, and the tonal separation between any two adjacent notes is a half tone, the whole row of reeds forming a chromatic scale progressing in uniform steps of one-half tone. The reeds on the lower reed plate 18 likewise progress in half-tone steps to form the chromatic scale and, as above stated, are played by blowing the breath. The extreme bass note, or the note at the extreme left end of assembly below the lower cell and played by blowing breath, is two half-tones lower in pitch than the note which is located above the upper left hand cell. Thus, if C were played by blowing in said lower cell, D, which is a full tone or two half-tones higher in pitch, would be played by drawing breath in the upper cell directly above said lower cell. All of the way up the scale the variance of tonal pitch is the same, so that each reed on the upper plate is two half-tones higher in pitch than the reed which is directly below it on lower plate. This "staggering" of tones is done in order that the mouthpiece may have a uniform spacing of holes and yet reach the desired combination of tones.

The musical tones comprising the major scale progress in steps of one whole tone or two half-tones between each two consecutive notes, except that the tonal separation between the 3rd and 4th and the 7th and 8th notes or intervals of scale is only one half-tone. This symmetrical arrangement of tones is not changed when the pitch of key is changed, but sharps and flats are required in the written music to maintain the proper tonal separation in the various keys. The key-transposing mouthpiece takes advantage of this fact, when used in combination with the above-described reed plate assembly. Preferably, the front portion of this mouthpiece 32 is constructed in the form of an elongated bar and tapers toward its front edge. A series of holes or air openings 33 pierce the front edge of such mouthpiece and are enlarged back of the front surface to form air cells which are separated from each other by partitions 34, as shown in Figure 3. The back portion of the said mouthpiece is recessed and shaped so as accurately to receive a stationary valve 35 (see Figure 4), this being a long, thin metal plate with air ducts piercing its upper and lower edges as shown, and also so as to receive a slideable air valve 36 such as shown in Figure 5, this valve being similar to valve 35, but having fewer air ducts and being shorter at its outer edges than valve 35 by an amount equal to the span of one of the air ducts 37 and being sufficiently narrower than valve 35 to allow it to slide freely in said recess. Such slideable interposing valve 36, as just described, should be flush with the rear edge of the mouth-

piece so that when the selector plate 39 is attached to said rear edge by means of screws 40, the slider will slide freely but not allow air to escape between it and the adjoining plates. The selector plate 39 (see Figures 3 and 10) is a metal plate having air ducts piercing its upper and lower edges, said ducts corresponding to those in stationary plate 35. The extreme upper and lower edges of plate 39 are curved backward and inwardly as at 41 to provide guide channels which will enclose and engage with the curved edges 28 of apertured valve plate 25 when the mouthpiece is mounted over the reed plate assembly. The slide valve 36 is interposed between two plates 35 and 39, which latter have duplicate air ducts therethrough, but since the valve 36 has fewer openings than have such plates, it fully controls the passage of air through the ducts in said plates 35 and 39.

In playing the harmonica, two consecutive notes of the scale are played through each hole, one of them being played by blowing and the other being played by drawing the breath. This interposing control valve 36 has an air duct 37 piercing its upper edge and a similar duct 38 piercing its lower edge to correspond with cells 42 in the mouthpiece. Thus, a blow note and a draw note is played through each air opening 33 in front edge of mouthpiece due to the fact that air duct 37 is directly over the row of reeds that are played by drawing the breath and air duct 38 is directly over the row of reeds that is played by blowing the breath. The proper arrangement, longitudinally, of these rows of ducts, such as that shown in Figure 5, will admit air to the proper sequence of blow and draw notes to play the complete harmonica scale in the normal manner without moving the mouthpiece. This holds true regardless of the longitudinal position in which the mouthpiece is set over the reed plate assembly, and the pitch of key will correspond to the note which is played by blowing in the opening at the extreme left end of mouthpiece.

It will be noted that almost any other arrangement of tones could be obtained by proper longitudinal spacing of these air ducts. One of these variations will be described later. A study of stationary valve 35 will show that it has a pair of air ducts 37a to correspond with each duct 37 in plate 36 and similarly it has a pair of ducts 38a to correspond with each duct 38 in plate 36. The normal position of slide valve 36 is to the left as shown in Figure 3, so that each duct in 36 will align with the left-hand duct of the aforementioned pairs. When the slide valve is moved to the right, the ducts 37 and 38 will align with the right-hand duct of each pair 37a and 38a.

Since all of the ducts thus opened will admit air to reeds which will be one-half-tone higher in pitch, the sharp of any note that was originally played will be obtained. This slide valve may be operated by a finger lever to obtain very rapid technique in playing sharps and flats as required in playing modern music. Such a lever 43 is indicated in Figures 1 and 2, it being a narrow strip of metal which encircles the reed plate assembly and pivots on pins 45 in ears 44, which are attached one to each side of the mouthpiece and preferably at the right-hand end of same. A forward extending pin 47 in the end of slide valve 36 engages in a properly aligned hole in the encircling lever so that when the rearward extending tab 46 is pressed to the left the slide valve will be moved to the right.

In the modification shown in Figure 11 there is illustrated a portion of the mouthpiece at the right end with the top cut away to disclose a spring 48 in position to hold the slide valve to the left in normal position. Spring 48 is held in place by a pin 49 extending from the top of the mouthpiece. A forward extending pin 50 in one edge of valve 36 extends through a slot 52 in stationary valve 35 into a vestibule 53 in end of the mouthpiece and one leg of spring 48 bears against this pin while the other leg of the spring bears against the right-end wall of the mouthpiece as shown. The lever 51 extends through a slot 50 in the side of the mouthpiece. This lever is mounted directly back of spring 48 and pivots on the same pin 49. The inward end of the lever is slotted to engage end of pin 50 and when outer end of lever is pressed to the left, the slide valve 36 will be moved longitudinally in a similar manner as by the lever 43 in Figure 1. Whether or not the type of lever 51 is used, the spring 48 will be employed to cause the valve to be returned to normal position and will be housed in substantially the same manner as herein described. While the lever 43 shown in Figure 1 is the preferred type of lever, it is desired that such lever not be limited to any specific construction as any form of lever usable for this purpose could be employed.

A varied form of slide valve 55 is shown in Figure 7 and the stationary valve which would be used with this slider is shown by 54 in Figure 6. In this case the face plate 39 would have ducts identical with those in the stationary valve 54 and again the slide valve will control the passage of air through said stationary valve plates. The purpose of this arrangement of valves is to lower certain tones of the musical scale without changing the others, to change the scale from major to minor key in construction. In this case the stationary valve has the right combination of ducts for the major scale with a few additional ducts 56 in the upper edge and 57 in the lower edge. These ducts are closed when slide valve 55 is in normal position and air will pass through the ducts 56a and 57a in slide valve to admit air to the normal notes. However, when the valve is moved to the right, these normal ducts are closed and slide valve ducts 56b and 57b will be in alignment with stationary valve ducts 56 and 57, respectively, thus lowering these notes one half-tone. The remaining notes will remain unchanged since additional ducts are provided to allow air to continue to flow through slide valve as before, as will be seen by studying the drawings. This is an example of one of the large number of possible changes of combination which may be accomplished by a slide valve of this type, by means of proper spacing of air ducts. The mouthpiece described along with this air valve arrangement lends itself to almost any desired result and it is not therefore desired to limit the longitudinal spacing of air ducts to any specific spacings, but rather to allow the arrangement of them in any desired manner to obtain the predetermined arrangement of notes.

In order that the mouthpiece may be easily and quickly adjusted from one key to another desired key, finger grips 58 and 60 are attached to the upper and lower sides, respectively, of the mouthpiece and extend far enough down the sides of the instrument so that they may be easily grasped by the thumb and forefinger. The lower grip 60 is in the form of a resilient spring and also acts as a locking release. The said resilient

grip is attached to the metal tab 59 as shown and the finger 61, which is a part of grip 60, swings through opening 62 in tab 59 so that curved lip 68 will bear against lower inward tapering edge 28 of apertured valve plate 25. This lip 68, striking edge 28 of 25, will wedge selector plate 39 of mouthpiece tightly to apertured plate 25 of reed plate assembly and thus prevent loss of breath between the two and also prevent longitudinal movement of mouthpiece. A short narrow tongue 69 is punched sharply inward in the center of lip 68 as shown in Figure 10 and drops in one of the spaced notches 70 in lower curved edge 28 as shown in Figure 8 to aid in setting mouthpiece accurately in desired position and to prevent any possibility of mouthpiece slipping. A pointer 67 forms a part of grip 58 and plays over a key indicating scale as stamped on the top cover 29. As an aid to the player in adjusting mouthpiece from one pitch of key to some other pitch of key while playing, a slender rearwardly extending finger 63 is punched inward of grip 58 and a depression 64 in finger 63 will drop in the various spaced depressions 66 in cover 29 when mouthpiece is moved longitudinally over reed plate assembly. The tension exerted by finger 63 is just sufficient to aid the player to count the number of half-tones when he moves the mouthpiece.

As a further and more positive aid in finding upper and lower pitches of key which will be required in playing any musical selection which modulates to two or more keys, a small clip 71 is provided. This clip or "stop" 71 is a narrow metal strip bent as shown in Figure 13. The ends 72 are curved to easily slip over edges of plate 25 and be frictionally retained by same. Depressions 73 will drop in the apertures in plate 25 and make a more positive lock against longitudinal movement of lock when in position. One of these stops may be placed on the left-hand portion of plate 25 at correct position to stop mouthpiece at the desired lower pitch of key and another one may be placed on the right-hand portion of plate 25 in position to stop mouthpiece from going above the desired higher pitch of key. They may be very quickly changed to desired limits. The above-described quick acting finger lock, the indicators and these stops all combine to give the player a superior control of harmonica while playing.

In the modern three octave, twelve hole, chromatic harmonica identical tones are played by blowing in the fourth and fifth holes and the same is also true of the eighth and ninth holes.

Since there is no repetition of notes in either row of reeds in this assembly, a special arrangement may be made whereby the same reed may be actuated by blowing in either the fourth or fifth hole and the same arrangement would be made in the eighth and ninth holes. Figure 12 is a portion of mouthpiece including the fourth and fifth holes looking at it from the front and Figure 14 is a cross-sectional view of same on line 14-14 looking in the direction of the arrows. A partition 74 extends through the fourth and fifth mouthpiece cells, and the cell separator 34 is omitted on the back side of this partition so that it forms one long cell. A port 76 pierces this partition in the portion within hole 4 and another port opens into hole 5. A leather valve 75 is mounted at the back of each port and this valve will allow air to enter the new air cell but will prevent it from re-entering either the fourth or fifth hole. This new elongated air cell covers

the rear air duct which admits air to the note in question, and air blown through either the fourth or fifth air openings will actuate this reed.

Means of preventing waste of breath past the reeds which are played by blowing, have already been described in the reed plate assembly hereinbefore set forth, and the method of preventing the escape of breath past the reeds which are played by drawing the breath will now be described. The valve wall 77 is constructed and inclined as shown in Figure 10 between each pair of cell separators 34 over the air ducts that admit air to the reeds that are played by drawing breath, or the upper row of ducts. An opening pierces this valve wall to allow breath to be drawn through same to actuate the reeds. In order that the breath may not be blown past these reeds when playing the blow notes, the end of a small leather valve 78 is, in each case, secured to an edge of the wall 77 and extended over the said openings and the pressure of the blown breath will close said valve. The mouthpiece would work without either of the latter two valve-controlling means mentioned, but it is desired to cover these controlling means as a possible means of constructing a more practical device.

My invention may be embodied in other specific forms without departing from the spirit or essential characteristics thereof. The present embodiment, as above set forth, is therefore to be considered in all respects as illustrative and not restrictive, the scope of my invention being indicated by the appended claims rather than by the foregoing description, and all changes which come within the meaning and range of equivalency of the claims are therefore intended to be embraced therein.

What I claim and desire to secure by Letters Patent is—

1. In a harmonica, the combination of a reed plate assembly having isolated rows of air cells and reeds extending over the mouths of said cells, an apertured plate secured to said reed plate assembly and admitting passage of air to said reeds, an adjustable key transposing mouthpiece mounted to move longitudinally upon said assembly, said mouthpiece having a series of air openings therethrough, a selector plate secured thereto and separating said openings from said assembly, and said selector plate having rows of air ducts therethrough in spaced relationship admitting the passage of air to pre-selected arrangements of cells and reeds in said rows.

2. In a harmonica, the combination of a reed plate assembly having isolated rows of air cells and reeds extending over the mouths of said cells, an apertured plate secured to said reed plate assembly and admitting passage of air to said reeds, an adjustable key transposing mouthpiece mounted to move longitudinally upon said assembly, said mouthpiece having a series of air openings therethrough, a selector plate secured thereto and separating said openings from said assembly, and said selector plate having rows of air ducts therethrough in spaced relationship admitting the passage of air to pre-selected arrangements of cells and reeds in said rows, and a valve mounted to move within said mouthpiece in sliding contact with said selector plate to control the passage of air through the air ducts of the same.

3. In a harmonica, the combination of a reed plate assembly having isolated rows of air cells and reeds extending over the mouths of said

cells, an apertured plate secured to said reed plate assembly and admitting passage of air to said reeds, an adjustable key transposing mouthpiece mounted to move longitudinally upon said assembly, said mouthpiece having a series of air openings therethrough, a selector plate secured thereto and separating said openings from said assembly, and said selector plate having rows of air ducts therethrough in spaced relationship admitting the passage of air to pre-selected arrangements of cells and reeds in said rows, and a valve mounted to move within said mouthpiece in sliding contact with said selector plate to control the passage of air through the air ducts of the same, and spring actuated means secured to said mouthpiece yieldingly holding said valve in normal position, and mechanism for manually operating said valve against said yielding means.

4. In a harmonica, the combination of a reed plate assembly having rows of cells and reeds extending over the mouths of said cells, an adjustable mouthpiece mounted to move longitudinally upon said reed plate assembly, said mouthpiece having a series of openings therethrough and an elongated recess located in the rear portion thereof, two air valves mounted within said recess one of which is stationary in position and the other of which is longitudinally movable therein, and a selector plate secured to said mouthpiece and acting as a cover for said recess, said valves and selector plate having rows of selectively spaced air ducts therethrough to permit passage of air to said reeds.

5. In a harmonica, the combination of a reed plate assembly, and a mouthpiece mounted to move upon said assembly and to be adjusted in various positions thereon, said mouthpiece having openings therethrough and a recess therein, two air valves mounted within said recess one of which is stationary in position and the other of which slides therein, a selector plate secured to said mouthpiece and covering said recess, said air valves and selector plate having selectively spaced air ducts therethrough permitting passage of air to said reeds.

6. In a harmonica, the combination of a reed plate assembly, a mouthpiece mounted to move upon said assembly and to be adjusted in various positions thereon, said mouthpiece having openings therethrough and a recess therein, two air valves mounted within said recess one of which is stationary in position and the other of which slides therein, a selector plate secured to said mouthpiece and covering said recess, said air valves and selector plate having selectively spaced air ducts therethrough permitting passage of air to said reeds, and spring actuated means affixed to said mouthpiece yieldingly holding said slideable valve in normal position, and manually operated means for operating said slideable valve against said yielding means.

7. In a harmonica, the combination of a reed plate assembly, a mouthpiece mounted to move upon said assembly and to be adjusted in various positions thereon, said mouthpiece having openings therethrough and a recess therein, two air valves mounted within said recess one of which is stationary in position and the other of which slides therein, a selector plate secured to said mouthpiece and covering said recess, said air valves and selector plate having selectively spaced air ducts therethrough permitting passage of air to said reeds, and finger grips attached to the mouthpiece whereby the mouth-

piece may be adjusted to and set in various longitudinal positions upon the reed plate assembly.

8. In a harmonica, the combination of a reed plate assembly, a mouthpiece mounted to move upon said assembly and to be adjusted in various positions thereon, said mouthpiece having openings therethrough and a recess therein, two air valves mounted within said recess one of which is stationary in position and the other of which slides therein, a selector plate secured to said mouthpiece and covering said recess, said air valves and selector plate having selectively spaced air ducts therethrough permitting passage of air to said reeds, finger grips attached to the mouthpiece whereby the mouthpiece may be adjusted to and set in various longitudinal positions upon the reed plate assembly, a metallic strip having a series of spaced indentations in one side thereof attached longitudinally to the reed plate assembly, and a resilient finger coupled to the mouthpiece and playing over said indentations.

9. In a harmonica provided with air cells and reeds thereover, a longitudinally movable mouthpiece mounted upon said harmonica and having a series of air openings therethrough to admit air to the reeds in any desired sequence, a series of longitudinally spaced depressions in the covering of said harmonica, and a resilient finger coupled to said mouthpiece and playing over said depressions to enable the performer to re-adjust the mouthpiece to any desired change of key while rendering a selection of music.

10. In combination with a harmonica having air cells and reeds thereover, a longitudinally movable mouthpiece mounted upon said harmonica and having a series of air openings therethrough to admit air to the reeds, means for directing the forced human breath to the desired combination of reeds, manually operated locking mechanism for tightening the association of said mouthpiece with said harmonica and preventing uncontrolled movement of said mouthpiece thereon, grips facilitating the longitudinal movement of said mouthpiece to desired positions upon said harmonica, together with a series of longitudinally spaced depressions in the cover of said harmonica and a resilient finger coupled to said mouthpiece and playing over said depressions whereby the player will be enabled to re-adjust the instrument to any desired change of key while playing.

11. In a harmonica, the combination of a reed plate assembly, a mouthpiece mounted to move upon said assembly and to be adjusted in various positions thereon, said mouthpiece having openings therethrough and a recess therein, two air valves mounted within said recess one of which is stationary in position and the other of which slides therein, a selector plate secured to said mouthpiece and covering said recess, said air valves and selector plate having selectively spaced air ducts therethrough permitting passage of air to said reeds, and detachable stops whereby the longitudinal movement of the mouthpiece may be limited within predetermined bounds.

12. A longitudinally movable adjustable mouthpiece for harmonica reed assemblies having rows of air cells and reeds thereover, said mouthpiece being constructed with a series of air openings through the front thereof, and having a selector plate assembly mounted upon the rear thereof and covering the back of said openings.

and said assembly being provided with rows of selectively spaced air ducts through the stationary portion of said plate assembly and having a 5 slideable air valve interposed in said assembly and controlling the passage of air through said air ducts.

13. A longitudinally movable adjustable mouthpiece for harmonica reed assemblies having rows of air cells and reeds thereover, said mouthpiece being constructed with a series of air openings 10 through the front thereof, and having a selector plate assembly mounted upon the rear thereof

and covering the back of said openings and said assembly being provided with rows of selectively spaced air ducts through the stationary portion of said plate assembly and having a slideable air valve interposed in said assembly and controlling the passage of air through said air ducts, and spring actuated means affixed to said mouthpiece 5 yieldingly holding said slideable valve in normal position, and manually operated means for operating said slideable valve against said yielding means.

WALTER R. STEELE.
